FIG. 3

FIG. 4

FIGURE 1 is a front elevation of a packaging machine for processed meat products, cheese, or the like, showing my new design.

FIGURE 2 is a top plan view of the machine shown in FIGURE 1.

FIGURE 3 is a right end elevation of the machine as shown in FIGURE 1.

FIGURE 4 is a perspective view of the machine shown in FIGURE 1.

The rear is substantially plain except as indicated in FIGURES 2 and 3.

Portions of the packaging machine are shown broken

away in FIGS. 2 and 3 in order to show indeterminate length and for convenience of illustration.

I claim:

The ornamental design for a packaging machine for processed meat products, cheese or the like, as shown and described.
